UNITED STATES PATENT OFFICE.

RICHARD H. WELLES, OF KENOSHA, WISCONSIN, ASSIGNOR TO THE BADGER BRASS MANUFACTURING COMPANY, OF KENOSHA, WISCONSIN, A CORPORATION OF WISCONSIN.

ELECTRICAL CONNECTOR.

1,054,810.

Specification of Letters Patent.

Patented Mar. 4, 1913.

Application filed April 17, 1912. Serial No. 691,434.

To all whom it may concern:

Be it known that I, RICHARD H. WELLES, a citizen of the United States, residing in the city of Kenosha, county of Kenosha, and 5 State of Wisconsin, have invented certain new and useful Improvements in Electrical Connectors, of which the following is a specification.

This invention relates to improvements in 10 electrical connectors and in the present instance is shown as applied to an electrically lighted headlight, although not necessarily confined to such use.

The salient object of the invention is to 15 provide simple and effective means for locking the connector plug within its shell or casing and in such a way that the plug may be readily removed and replaced without the necessity of using screws, or other tool 20 operated locking means; also to provide a construction in which the foregoing object is obtained by means of a simple U-shaped locking member or C-cotter and in general to provide an improved construction of the 25 character described.

The invention consists in the matters hereinafter described and more particularly pointed out in the appended claims.

Referring to the drawings—Figure 1 is a 30 vertical sectional view of an electrically lighted headlight equipped with my invention; Fig. 2 is a perspective view showing the parts unassembled; Fig. 3 is a vertical sectional view of the parts assembled; Fig. 35 4 is a view taken on lines 4—4 of Fig. 3; Fig. 5 is an enlarged horizontal sectional view taken on lines 5—5 of Fig. 1.

In the drawings—1 designates an electrical headlight of well known type, to the 40 lower end of which is fixed a bushing 2, through which extends a cylindrical shell or casing 3, which forms a lamp fixture and also serves as a casing for the various contact terminals hereinafter described. Within 45 the shell 3 is mounted the usual contact plug 4, made of insulating material and cylindrical in form as shown in the drawings. This plug is bored to receive the upper contact pins 5, 5, and lower contact 50 pins 6, 6, which are spring supported as shown at 7. The contact pins and their expansion springs 7 are preferably mounted in sleeves 8, all in the usual manner.

The upper end of the sleeve or shell 3 receives the base 9 of the lamp L. The latter

is locked to the sleeve by pins 10 engaging bayonet slots 11 in the upper end of the sleeve or casing. The lower end of the lamp base has contact plates 12 which engage the upper pins 5 and are held in electrical contact therewith by the springs 7.

Within the lower end of the casing 3 is secured a cylindrical insulating block or plug 13 which receives the metal terminal tips 14 which engage the lower contact pins 6 as shown clearly in Fig. 4. The lower end of each terminal tip is suitably soldered or otherwise secured to the supply conductors 15. The plug 13 is detachably locked to the casing by pins 13' engaging a bayonet slot 14'. A removable screw threaded cap 16 covers the parts and prevents the plug working loose. In order to prevent short circuiting of the terminals 14 when the plug is removed, I provide the insulating block 13 with a projection 17 which bridges the contact screws 18 which form the upper ends of the terminal tips 14. In like manner the lower end of the plug 13 is provided with an insulated extension 19 which fits between the conductors 15 and prevents the latter being squeezed together and thus short circuiting. This extension 19 is curved so as to fit around the conductors 15. These insulating extensions however, form no part of the present invention and need not be further described.

Referring now to the manner of locking the connector plug 4 within the casing which forms the salient object of the invention, the plug 4 is provided with a pair of oppositely disposed grooves 20, near its upper end, formed by recessing the sides of the plug or insulating block. Directly opposite the grooves 20 the casing 3 is slotted as shown at 21, the slots 21 being directly opposite the grooves 20 when the plug is in its position within the casing. The plug is locked in this position by means of a U-shaped spring gripping member 22 having parallel spring arms 23 entering the slots 21 and engaging the grooves 20 of the plug. The arms tend to spring inwardly and the arrangement is such that the plug is effectively locked to the casing. The U-shaped gripping member or reverse C-cotter which it may be called, since it acts the reverse of a cotter pin and serves the same purpose, is obviously readily snapped in position or removed from the

connector. Nevertheless, its spring grip is such as to obviate any possibility of its working loose and releasing the connector plug. The position of the grooves 20 and 5 slots 21 may be more or less varied as long as they are in register, and the shape of the member 22 may also be modified.

The essence of the present invention consists in its simplicity and economy of construction combined with its effectiveness in performing its function. The disadvantages which result from the shearing off or working loose of screws in constructions heretofore used, is obviated. In addition, the casing and insulated plugs may now all be connected without the use of a screw-driver or other tools.

In its broader aspect the invention is not limited to the details of construction shown.

20 I claim as my invention:

1. In an electrical connector the combination with a hollow shell-like cylindrical casing, terminal plugs having contact devices and detachably connected at either end of said casing, a cylindrical connector plug detachably seated within said casing and provided with contact pins for affording electrical connections between the contact devices of the terminal plugs, said connector plug having oppositely disposed grooves at 25 its periphery registering with similarly formed slots in the periphery of the casing

and a U-shaped spring gripping member engaging said slots and grooves for detachably locking the connector plug to the casing. 35

2. In an electrical connector, the combination with a cylindrical shell like casing, of a terminal plug detachably engaging either end of said casing, said terminal plugs having contact devices, a grooved connector 40 plug interposed between the terminal plugs and having contact pins engaging the contact devices of said latter plugs, said casing being slotted opposite the grooved portion of the connector plug and a U-shaped spring gripping member engaging the fitting in 45 said slots and locking the connector plug to the casing.

3. In an electrical connector, the combination with a cylindrical shell-like casing, of a 50 connector plug within said casing, said plug having oppositely disposed grooves in its periphery registering with slots formed similarly in the casing and a spring gripping member having arms engaging the slots 55 and grooves and detachably locking the connector plug to the casing, said spring gripping member being confined in position solely by its spring gripping engagement with said grooves and slots.

RICHARD H. WELLES.
